(57) **CLAIM**

The ornamental design for a drill bit cutter element as shown and described.

DESCRIPTION

FIG. 1 is a front perspective view of a drill bit cutter element according to the new design;

FIG. 2 is a side, perspective view of the drill bit cutter element of FIG. 1;

FIG. 3 is a back, perspective view of the drill bit cutter element of FIG. 1;

FIG. 4 is a front view of the drill bit cutter element of FIG. 1;

FIG. 5 is a back view of the drill bit cutter element of FIG. 1;

FIG. 6 is a left-side view of the drill bit cutter element of FIG. 1;

FIG. 7 is a right-side view of the drill bit cutter element of FIG. 1;

FIG. 8 is a top view of the drill bit cutter element of FIG. 1; and,

FIG. 9 is a bottom view of the drill bit cutter element of FIG. 1.

(Continued)

The broken lines in the drawings illustrate portions of the drill bit cutter element that form no part of the claimed design.
